UNITED STATES PATENT OFFICE.

FRIEDRICH HEROLD, OF BUCHHOLZ, SAXONY, GERMANY.

DESIGN FOR A WALL-RECEPTACLE.

44,922.

Specification for Design.

Patented Nov. 25, 1913.

Application filed September 2, 1913. Serial No. 787,805. Term of patent 7 years.

To all whom it may concern:

Be it known that I, FRIEDRICH HEROLD, a subject of the German Empire, residing at Buchholz, in Saxony, Germany, have invented a new, original, and ornamental Design for Wall-Receptacles, of which the following is a specification, reference being had to the accompanying drawing, forming part thereof.

Figure 1, is a perspective front elevation and Fig. 2, a vertical cross section in the line $a-a$, of a wall receptacle, showing the new design.

I claim—

The ornamental design for a wall receptacle, as shown.

In witness whereof I have hereunto set my hand in the presence of two subscribing witnesses, at Chemnitz, in Saxony, Germany, this 11th of February, 1913.

FRIEDRICH HEROLD.

In presence of—

E. KILBOURNE FOOTE,
EMIL STEGER.
